UNITED STATES PATENT OFFICE

WILLIAM J. FENDER, OF MINNEAPOLIS, MINNESOTA.

IMPROVEMENT IN MIDDINGS-PURIFIERS.

Specification forming part of Letters Patent No. 159,505, dated February 9, 1875; application filed January 14, 1875.

To all whom it may concern:

Be it known that I, WILLIAM J. FENDER, of Minneapolis, in the county of Hennepin, in the State of Minnesota, have made certain Improvements in Middlings-Purifiers, of which the following is a specification:

The object of this invention is to simplify the construction and perfect the operation of purifying middlings in passing through the machine; and it consists in the construction, arrangement, and combination of parts, as will be fully hereinafter described.

In the drawings, Figure 1 represents a side view of the machine; Fig. 2, a longitudinal section; Fig. 3, an end view, and Fig. 4 a transverse upright sectional view.

A represents the main frame of the machine; A', the casing or lining. A'' are the two longitudinal side girts, and between which the shaker reciprocates. a is a sliding door to opening a' through the side girts A'', and on a line with the brush that traverses the sieve on the edge of the shaker. B is the main driving-shaft passing transversely through the upper part of the machine, and has the suction-fan B' centrally located thereon. B'' is the driving-pulley on one end of shaft B, and B''' is a band-pulley on the opposite end of shaft B. b is a belt around pulley B''', to and round pulley C on short horizontal shaft C', and gives motion to said shaft C' and its connections. b' is an eccentric, fast on shaft B, and revolving with it. b'' is a yoke encircling and actuated by the eccentric b'. D is the receiving-hopper, formed by the inclined side D' and opposite side d. d' is an adjustable sliding gate or gage, and is adjusted upon side d, and held when adjusted by holding-screw d'', so that the amount of meal is regulated at opening d''' that shall pass into the machine. E is the bottom of the receiving-hopper, is in form of a segment of a circle, the center of which is at e. E' E' are arms that are fast to the ends of E, and are pivoted to the frame of the machine at e, in such manner that the bottom E can freely oscillate to feed the meal into the machine, and prevent clogging. e' e' are arms attached to the under side of the oscillating bottom E. F is a rock-shaft placed transversely across the machine, and working in proper bearings at-

tached to the frame A. ff are crank-arms projecting from shaft F, and connect with arms e' on the under side of the hopper-bottom, to give the necessary oscillating motion to the bottom E, and are adjustable thereon to compensate for lost motion by the lugs e''. f'' is a spring connecting-rod or pitman attached at one end to yoke b'', and at the other to a crank-pin on crank, f', on rock-shaft F. As the eccentric b revolves with shaft B it vibrates the crank f' and rock-shaft F, which gives the oscillating motion to the bottom E through the spring connecting-rod f''. This rod f'' is made elastic or yielding, in order to prevent breaking, as there is another connecting-rod that is rigid, and attached to yoke b'', and communicates motion in another direction; hence one must give in order to prevent breaking of parts, as it would probably do if both connecting-rods were non-yielding.

By this construction of parts the feeding of the meal into the machine is regulated, and all liability to clogging is prevented, as it will be observed that the curvature of the feeding bottom of the hopper is inclined downward at or toward the feed-opening d''', and the opposite or highest part passes under and in close contact with the inclined side D' of the hopper. No particles can be retained upon it, but all must pass through evenly at the opening d'''.

G is an inclined open frame fast between pivoted arms E', and oscillates with them, and on the upper side has bolt-cloth g secured, and on its upper and outer edge has a perpendicular face-board, g', projecting upward, to receive and conduct all the meal as it is fed from the bottom E into the machine, the cloth on the inclined frame acting as the means of distributing the meal evenly the whole width of the frame into the shaker. H is an inclined transverse partition, extending up to near the top of the machine, where there is hinged a flap-valve, h, to regulate the opening between it and the under side of the top casing of the machine into the exhaust-chamber. This partition conducts the meal evenly into the shaker. h' h' h'' are inclined gathering-slats with air-openings h'' between them to admit a current of air to pass through the sieve or bolt-cloth g, and impinge against and pass through the meal as it

falls from the cloth g , through the narrow opening h''' , thence into the shaker. I is the shaker, composed of a rectangular frame, and covered with a cloth, i , of the requisite mesh to sort the grains of middlings on its bottom or lower side, is of such width as to freely slide inside the width of the frame and casing of the machine, and is suspended at four points by four projecting rods, i' , that work in upright vibrating arms i'' that are connected adjustably in horizontal slots i''' in the slotted plates i^4 , that are adjustable vertically by a holding-screw in the vertical plates. J is a connecting-rod or pitman, connected at its upper end to yoke b'' over the eccentric b' , and at its lower end is adjustably connected to crank-arm j on horizontal transverse shaft J' . Rigidly fixed to shaft J' are two projecting arms, j' , that engage with adjustable lugs j'' on the outside of the shaker-frame I, so that as the eccentric b' revolves it will, through the yoke b'' and pitman J, give a short horizontal reciprocating motion to the shaker I. The adjustable lugs j'' on the side of the shaker are made in separate parts, and each part to be adjusted to compensate for wear, either of the arms j that bear upon the lugs to actuate the shaker, or of the lugs themselves, and for lost motion when either part is worn so that there would be play between the arm and lugs.

The horizontal reciprocations of the shaker are graduated to be more or less by adjusting the connecting-rod J upon the crank-arm j . Short horizontal shaft C' has a miter gear-wheel, c , fast upon it, and gears into another miter gear-wheel, c' , on vertical shaft c'' , and gives motion to upright shaft, and to the worm or spiral gear-wheel c''' , which gears into teeth on wheel K that is on a horizontal shaft projecting longitudinally from the end of the machine. L is a connecting-rod, adjustably connected to one of the radial arms of toothed wheel K at k , and thence with the segmental toothed wheel L' at k' . Toothed segmental wheel L' is pivoted at l , so as to freely vibrate upon its pivot. L'' is a toothed pinion on a horizontal shaft, gearing into segmental wheel L' , and as wheel K makes one revolution it actuates the segmental gear to vibrate back and forth, which in turn causes the pinion L'' to make a revolution in one direction as the segmental gear vibrates one way, and when the opposite vibration of the segmental gear takes place the pinion L'' makes a reverse revolution. O is a horizontal longitudinal shaft, revolved by pinion L'' , and upon which, and near each end of the machine, are secured pulleys O' that revolve with shaft O, and make a revolution in reverse directions the same as pinion L'' . $o\ o\ o\ o$ are pulleys at the sides of the machine, and made secure thereto so as to freely revolve in either direction. $o'\ o'$ are bands, each one fastened at either end to one of the pulleys O' , and then passing over side pulleys o , and attached to the brush. These bands are wound around pulleys O, so that as the pulleys make a complete revolution and

are then caused to reverse and make a revolution in the reverse direction, they cause the brush to sweep the bolt-cloth alternately in both directions. P is a brush extending longitudinally the entire length of the under side of the bolt-cloth on the shaker-frame, and is rigidly connected to the bands $o'\ o'$, and as the band is forced in opposite directions the brush P is carried transversely and completely across the entire width of the shaker-frame, and its motion is reversed after the brush has passed off of the bolt-cloth, and while it is in contact with the frame of the shaker, which prevents the wear upon the bolt-cloth that takes place when the motion of the brush is reversed while bearing upon the bolt-cloth. $p\ p$ are downward projections on the under side of the shaker-frame, and form wipers to clear the brush from all adhering particles of meal or dust, as the brush passes under and past them before reversing its course of travel.

By this means the brush is cleared of meal before its return movement across the bolt-cloth, which is necessary to have done, for, as the brush is always in an upright position, some means must be adapted to clear the meal out that is unavoidably held in the brush, or else the brush would fill entirely and be useless for keeping the meshes of the bolt-cloth clear by its action. $p'\ p'$ are supports and guides to the brush in its reciprocations across the bolt-cloth. $p''\ p''$ are gathering-slats on each side of the machine, to gather the middlings after they have been purified, with air-spaces p''' between them. Q is a conveyer to deliver the purified middlings to a proper receptacle, and is revolved by gear-wheel q on shaft C' , and the wheel q' on the shaft of the conveyer. The suction-fan B', being in motion, causes a current of air from the outside of the machine, through openings h'' and p''' , into the machine. The air that is caused to pass in through spaces h'' strikes the meal as it is being evenly spread on the cloth g of the vibrating frame G, and as it falls off the cloth toward and upon the inclined partition H, to the aperture h''' , when the first separation of dust and light particles from the middlings takes place, and such light particles pass off with the current of air into the exhaust-fan, and forced to make exit at the opening R out of the machine. The valve h is used to control the force of the passing current into the exhaust-fan. The air that passes in through spaces p''' is caused to pass upward through the bolt-cloth on the shaker I, where it comes directly in contact with the middlings in agitation on the shaker, when the second separation takes place by the remainder of all light particles with the middlings being floated off with the current of air up through openings $s\ s\ s$ in the ceiling of the machine over the shaker, then forced out of the machine through the exit-opening R by the exhaust-fan B'. All particles too heavy to be separated by the two applications of currents of air, and too large to pass through the meshes of the bolt-

cloth, are passed off of the tail end of the shaker and disposed of in the usual manner. $s' s' s'$ are valves to regulate the current of air that passes through openings s . $s'' s'' s''$ are deflectors placed under the openings s , to more equally distribute the currents of air in passing out of the chamber above the shaker.

A brush traversing the bolt-cloth transversely back and forth the entire width of the shaker, and reversing its direction off of the cloth, is a great improvement over old methods, where the brush travels in one direction only, and more than one-half of the time does not act upon the cloth, or where a series of brushes having short reciprocations, and reversing their direction of reciprocation upon the cloth is used.

Having thus described my invention, what I claim is—

1. The feeding-device composed of the vibrating bottom E , pivoted arms E' , arms e' , adjustable connection e'' , and distributer G , in combination with the devices that actuate them, substantially as described.

2. The inclined gathering-strips h' and openings h'' between them, to admit air that is made to impinge upon the meal and separate the light particles from the middlings before the middlings fall into the shaker, in combination with the distributer G , substantially as described.

3. The combination, with the eccentric b' , of the yoke b'' , the yielding connecting-rod f'' , and rod J , rigidly connected to yoke b'' , whereby motion is given to a vibrating feed device and a reciprocating shaker from the same shaft, substantially as described.

4. The combination of the rock-shaft J' , arm j' , and adjustable lugs $j'' j''$, with the shaker I , constructed and operating substantially as described.

5. The combination of the revolving worm-gear wheel c''' , toothed wheel K , connecting-rod L , segmental gear L' , pinion L'' , shaft O , pulleys O' , band o' , and guides p' with the brush P , substantially as described.

6. The projections $p p$ on the under side of the shaker-frame I , in combination with the reciprocating brush P for cleaning it, substantially as described.

7. In a machine for purifying middlings, the transversely-reciprocating brush P , arranged to be carried across the entire width of the bolt-cloth of the shaker, and reversing its movement off of the cloth, and returning in the opposite direction in the same plane, substantially as and for the purpose described.
